his Attorney.

UNITED STATES PATENT OFFICE.

FREDERICK VAN DYKE, OF DETROIT, MICHIGAN.

LUBRICATING ATTACHMENT FOR THREAD-CUTTING DIES.

1,294,851.

Specification of Letters Patent.

Patented Feb. 18, 1919.

Application filed May 29, 1918. Serial No. 237,293.

To all whom it may concern:

Be it known that I, FREDERICK VAN DYKE, a subject of the Queen of the Netherlands, and a resident of Detroit, in the county of Wayne and State of Michigan, have invented certain new and useful Improvements in Lubricating Attachments for Thread-Cutting Dies, of which the following is a specification.

10 This invention relates to a lubricating attachment for thread cutting dies, and an object of the invention is to provide an oil can which is detachably carried by one of the handles of a die stock, the spout of which can extends longitudinally along the stock, and has its outlet positioned so that the oil or lubricant ejected therefrom will engage the work or article upon which the threads are being cut.

20 It is well-known, that to insure the efficient operation of thread cutting dies, it is necessary to lubricate the cutting edges of the dies, and also the material upon which the threads are being cut. This is commonly done through the medium of an ordinary oil can from which lard oil or similar light-bodied lubricant is forced upon the die, but in using an ordinary oil can it is necessary to stop or arrest the rotating movement of the die and stock to apply the lubricant thereto.

It is an object of this invention to provide an oil can particularly designed for attachment to one of the handles of a die stock whereby the lubricating oil may be fed to the die and article being worked upon during the working operation of the die, eliminating the necessity of stopping the operation of the die to apply lubricant thereto.

40 Other objects of the invention will appear in the following detailed description, taken in connection with the accompanying drawings, forming a part of this specification and in which drawings:

45 Figure 1 is a plan view of a die and stock showing the improved lubricator applied thereto.

Fig. 2 is a side elevation of the die and stock showing the lubricator or oil can applied thereto.

Fig. 3 is a bottom plan of the oil can.

Fig. 4 is a longitudinal section through the can.

50 Fig. 5 is a cross section through the can and stock showing the manner of connecting the can to the stock.

Referring more particularly to the drawing, A designates a die stock of the usual construction carrying the cutting dies B and having the usual type of handles C so connected thereto for operating the same.

The improved lubricator, is generically indicated by the numeral 1 and comprises, specifically, an oil can having a rectangular shaped body 2 provided with a longitudinally extending substantially semi-circular instruck portion 3 forming a recess for receiving a portion of one of the handles C of the die stock A to connect the oil can to the handle. The body 2 has a contractile spring 4 connected thereto which extends about the portion of the handle C projecting out of the recess 3 and has an eye 5 carried at one end which engages over a hook 6 attached to the bottom of the can upon the opposite side of the recess from the point at which the spring 4 is attached to the can, as clearly shown in Fig. 5 of the drawing, and for yieldably attaching the oil can to the handle C of the die stock A. The upper corners 60 of the can are cut away, as clearly shown in Figs. 1 and 5 of the drawing to prevent protruding sharp corners which might catch upon the sleeve of the operator. The forward end 7 of the can 1 is reduced, having 65 its under surface flat for engagement against the handle C and its upper and side surfaces converging, forming a reduced mouth or outlet portion 8 to which the spout 9 of the can is connected. The spout 9 extends longitudinally along the handle C and the stock A and has its outlet positioned whereby the oil or lubricant forced from the can body 2 will be fed to the die B for lubricating the cutting surfaces of the die and also lubricating the surface of the objects being worked upon.

The spout 9 is detachably connected to the body of the oil can in the usual manner, to permit its disconnection from the can to fill the latter.

Having thus fully described the invention, what is claimed is:

1. The combination with a die stock and die carried thereby, of an oil can having one side shaped to snugly fit one of the handles of said stock, means for detachably connecting said oil can to said stock, said can having a spout the outlet of which is positioned for delivering lubricant to the die carried by the stock.
2. The combination with an ordinary

3
2. Thread cutting die stock and dies carried thereby, of an oil can provided with an instruck portion adapted to engage over a part of the die stock, yieldable means for holding said can connected to the die stock, the spout of said oil can positioned for delivering lubricant to the die carried by the stock.

3. The combination with an ordinary thread cutting die stock and a die carried thereby, of an oil can embodying a substantially rectangular body having a substantially semi-cylindrical instruck portion in its under surface adapted to engage over a portion of the die stock, a contractile spring connected to said can for engagement about the die stock to yieldably connect said can to said stock.

4. The combination with an ordinary thread cutting die stock and a die carried thereby, of an oil can embodying a substantially rectangular body having a substantially semi-cylindrical instruck portion in its under surface adapted to engage over a portion of the die stock, a contractile spring connected to said can for engagement above the die stock to yieldably connect said can to said stock, the forward end

of said can being reduced in thickness and having its sides and upper surface tapering to a converged outlet, and a spout connected to said converged outlet and leading over the die stock to deposit lubricant ejected therefrom upon the die carried by the stock.

5. As a new article of manufacture, an oil can comprising a substantially rectangular body having a substantially semi-cylindrical instruck portion formed longitudinally in one side thereof, the forward end of said can being reduced in thickness and having its sides and upper surface tapering to form a converged mouth, and a spout connected to said converged mouth.

6. As a new article of manufacture, an oil can comprising a substantially rectangular body provided with a longitudinally extending substantially semi-cylindrical instruck portion in one side thereof, and a contractile spring having one end connected to the can at one side of the instruck portion, and a hook carried by the can upon the other side of the instruck portion and adapted for detachable engagement with one end of said spring.

FREDERICK VAN DYKE.
